Ralph La Rue Dubois, 4242 E. 111th St.,
Tulsa, Okla. 74135

Filed Sept. 22, 1969, Ser. No. 19,251

Term of patent 14 years

Int. Cl. D9—99

U.S. Cl. D52—2

FIG. 1

FIG. 2

FIG. 4

FIG. 1 is a front elevational view of a disposable cup dispenser showing my new design.

FIG. 2 is a side elevational view taken from one side, the opposite side being a mirror image of the side shown; and

FIG. 3 is a top plan view.

FIG. 4 is a bottom plan view thereof.

The rear side of the design is substantially plain and unornamented.

A portion of the disposable cup dispenser is stippled to indicate a contrast in appearance.

I claim:

The ornamental design for a disposable cup dispenser, substantially as shown and described.
